G. P. Goepel
ATTORNEY

UNITED STATES PATENT OFFICE

DAVID KARRON, OF BROOKLYN, NEW YORK

HAND BAG

Application filed December 6, 1929. Serial No. 412,067.

This invention relates to hand bags, and more particularly to a frame for ladies' hand bags and the like embodying ornamental jaw members, and means for hingedly connecting said jaw members with each other consisting of structurally independent elements with simple, inexpensive and effective means whereby said elements and the jaw members may be rapidly assembled and secured in fixed relation to each other.

In one embodiment of the invention, the jaw members are formed from a suitable ornamental material, such as celluloid or pyroxylin and are of channel shaped form in cross section, said channels receiving the usual hingedly connected metal frame elements which are clinched upon the edges of the bag material. The metal frame elements and the ornamental jaw members are further provided with contiguous integral portions, one of which is bent relative to the other and in clinched engagement on the latter, thereby permanently securing said jaw members and frame elements together against separation and eliminating the necessity of applying rivets or other supplemental fastening or securing elements for this purpose.

With the above and other objects in view, the invention consists in the improved handbag frame and in the form, construction and relative arrangement of its several parts as will be hereinafter more fully described, illustrated in the accompanying drawing, and subsequently incorporated in the subjoined claim.

In the drawing, wherein I have disclosed one simple and practical embodiment of my present improvements, and in which similar reference characters designate corresponding parts throughout the several views,

Figure 1 is a side elevation partly in section, showing one preferred construction of my new handbag frame;

Fig. 2 is an enlarged transverse sectional view taken on the line 2—2 of Fig. 1;

Fig. 3 is a detail fragmentary end elevation, and

Fig. 4 is a detail perspective view of the hingedly connected end portions of the

metal frame elements and the ornamental jaw members before the parts are assembled.

Referring in detail to the drawing, 5 designates the usual channel form sheet metal frame elements within which the edges 55 of the opposite flexible side walls of the bag indicated at 6 are secured in the usual manner, by clinching the opposite side flanges of the elements 5 upon the material. As herein shown, these frame elements are of 60 general inverted U-shaped contour and at their extremities are formed with apertured ears indicated at 7 to receive suitable hinge pins or grommets 8.

Jaw members 9 are superimposed upon 65 the metal frame elements 5 and provide an ornamental trim or covering therefor. These jaw members may be of celluloid of any selected color, and are preferably formed from sheet material, said material 70 being suitably cut and bent to provide a continuous jaw member of the same general contour as the frame element 5 and also of channel shaped form in cross section. Within the channels of the ornamental members 9, the hingedly connected frame elements 7 are respectively snugly fitted so that as seen in Fig. 2 of the drawing, said metal frame elements are completely covered and concealed by the superimposed ornamental 75 jaw members 9.

Each of the members 9 is provided in suitably spaced relation to each end thereof and in its intermediate portion with a slot or opening shown at 10, and at points correspondingly spaced from the ends of the metal frame elements 5, the intermediate walls of these elements are provided with outwardly struck tongues 11. Before assemblage of parts, these tongues 11 extend at right angles to the end portions of the frame elements 5 as shown in Fig. 4 of the drawing, and in applying the ornamental jaw members 9 upon said metal frame elements, the end portions of the former may 85 be resiliently sprung outwardly to a sufficient extent to enable the same to ride over the outwardly projecting tongues 11. When the intermediate portion of the jaw member comes into contact with the intermediate 90

part of the frame element 5, the tongues 11 will then be in registering relation with the openings 10 and will be received therethrough, the end portions of the jaw members 9 returning to their normal positions and in close engagement with the outer sides of the opposite end portions of the frame elements 5. The lugs 11 are then angularly bent inwardly towards the hinge ears 7 of the frame elements 5 and securely clinched upon the intermediate portions of the jaw member 9 at the ends thereof. These clinched tongues will permanently retain the parts in assembled relation without requiring the use of rivets or other supplemental fastening means therefor.

Upon the outer side of one of the jaw members 9 and on the horizontal portion thereof, a suitable latch element indicated at 12 is mounted at one of its ends for pivotal movement by means of a suitable rivet or stud 13 passing transversely through the jaw member and the associated metal frame element 5. This latch member is adapted to embrace the two jaw members to hold the latter in tightly closed position.

From the foregoing description considered in connection with the accompanying drawing, the construction and arrangement of the various parts constituting the novel features of the present disclosure together with the advantages thereof will be clearly understood. It will be seen that by the provision of the integral connecting means whereby the metal frame elements and the ornamental jaw members mounted thereon may be secured together, that these parts can be very easily assembled with great rapidity, and without necessitating the employment of skilled labor or the use of special riveting machines. Thus quantity production of such handbag frames will be ma-

terially increased with a lessening in labor and manufacturing cost.

While I have shown a particular form of the integrally formed connecting means between the frame parts, it will be understood that this means in its details might be otherwise formed or constructed, and that the general contour of the frame parts as well as their cross sectional form might also be varied. It is accordingly to be understood that the privilege is reserved of resorting to all such legitimate changes in the form, construction and relative arrangement of the several parts of the device as may be fairly embodied within the spirit and scope of the invention as claimed.

I claim:

In a handbag frame, a pair of ornamental trim members of sheet material each having a continuous groove or channel, and means for hingedly connecting said members with each other consisting of metal frame elements hingedly connected at their ends and adapted to be respectively snugly fitted in the channels of said trim members, said frame elements being also of channel shaped cross sectional form to be clinched upon the marginal edges of the handbag material, and said elements in their intermediate portions and adjacent their hingedly connected ends being provided with outwardly struck tongues, said ornamental trim members having relatively yieldable end portions provided with openings therethrough to receive the tongues on the respective frame elements when said trim members are superimposed thereon, and said tongues adapted to be clinched inwardly upon the outer surfaces of said trim members to permanently secure the parts in assembled relation.

DAVID KARRON.
